No. 798,676.

PATENTED SEPT. 5, 1905.

C. HALLER.
ELECTRIC SIGN.
APPLICATION FILED OCT. 19, 1904.

UNITED STATES PATENT OFFICE.

CARL HALLER, OF CHICAGO, ILLINOIS, ASSIGNOR TO THE HALLER MACHINE COMPANY, OF CHICAGO, ILLINOIS, A CORPORATION OF ILLINOIS.

ELECTRIC SIGN.

No. 798,676.

Specification of Letters Patent.

Patented Sept. 5, 1905.

Application filed October 19, 1904. Serial No. 229,187.

To all whom it may concern:

Be it known that I, CARL HALLER, a citizen of the United States, residing in the city of Chicago, county of Cook, and State of Illinois, 5 have invented a new and useful Improvement in Electric Signs, of which the following is a specification.

My invention relates to electric signs wherein in the letter outline is illuminated by incandescent lamps; and the objects of the invention are, first, to simplify the construction so that a sign may be produced with a minimum expenditure of time, labor, and material; second, to combine lightness of weight with 15 stiffness and rigidity, and, third, to provide the other details hereinafter set forth. I attain these objects by the means illustrated in the accompanying drawings, in which—

Figure 1 is a face view of a sign embodying my invention. Fig. 2 is a sectional view thereof, taken on the line 2 2, Fig. 1. Fig. 3 is a rear perspective view of a letter-outline shell or casing. Fig. 4 is an enlarged fragmentary view showing a portion of the rim and also showing the lamp-sockets attached to the back plate and provided with their electric connections. Fig. 5 is an enlarged fragmentary view similar to Fig. 2. Fig. 6 is similar to Fig. 5 except that the lamps and shell are removed. Fig. 7 is a sectional view of a portion of a letter-shell drawn to the same scale as Figs. 5 and 6. Fig. 8 is a development of a corner portion of the metal sheet of which in the preferred construction 35 the back plate is formed.

Similar letters refer to similar parts throughout the several views.

The back plate consists, preferably, of a single sheet of metal cut at the corners in the 40 manner illustrated in Fig. 8 and subsequently bent so as to form the central letter-bearing portion *a*, the riser *b*, the facing *c*, the outer wall *d*, and the flange *e*.

In order to facilitate attachment to a wall 45 or other object upon which the sign is to be supported, the wall *d* is of a greater height than the riser *b*. By this construction also a space is afforded for the electric wiring and connections between the central sign portion 50 *a* and such wall or outer supporting object. The same would be true when instead of being attached to a wall two back plates are secured together back to back to form a double-faced sign, such as are commonly employed

when the sign is to project out over the side-walk.

It is obvious that when the back plate is formed in the manner shown, the box-like rim imparts great stiffness and rigidity and yet adds but little to the weight of the sign. 60

The lamp-sockets *f* are secured directly to the back plate and arranged thereon in such manner as to form the outline of the letters. The wires *f'* lead from one socket to another on the front of the plate to furnish the necessary current; but the wires *f''*, leading from the source of supply or leading from one letter to another, are brought through suitable apertures in the back plate, so that the wiring may be invisible from the front. After 70 the sockets are fixed in position the letter shells or casings *g* are placed over them. These shells or casings form the letters and are box-like members, except that they are open at the back, where they are provided 75 with ears or flanges *g'*, whereby they are soldered or bolted or otherwise secured to said back plate. By preference the height of the letter-shell is slightly greater than the height of the sockets, so that said sockets may be 80 protected from the weather. In the top or face of the letter-shells are the apertures *g''*, which register with the sockets *f*, so that the lamp *h* may be inserted thereinto.

One of the important features of this invention lies in the fact that the sockets *f* are attached directly to the plate which forms the general backing of the sign. During the manufacture one workman may be occupied in permanently attaching the sockets to the back 85 plate without reference to any secondary or intermediate piece, while another workman may be simultaneously engaged at a distance in constructing the shells themselves. When both are independently completed, the casings, 90 which are light in weight and easily handled, are simply placed over the sockets and secured in position. There is required no fitting or joining of the different parts of a letter and no transporting while the sockets are within, 95 as is the common method of to-day. The lamp-sockets in the aggregate have considerable weight, and by the old method the letters must be made strong enough to carry them. In this construction, on the contrary, the 100 weight of the sockets is all carried by the back plate, and the shells are simply to supply the letter outlines. By this construction also 105

a separate backing for the letters becomes superfluous, and consequently there is a saving in time and labor, material, and weight.

By preference the letter-casings at any given

5 cross-section consist of a single piece of metal, and as this is also true of the back plate it follows that the completed sign may readily be made completely waterproof. Of course if one sheet of metal employed in the manu-
10 facture of the sign has not sufficient superficial area to form the entire back and rim plate or the entire letter-shell said sheet of metal may be supplemented by being soldered or riveted to another sheet; but in this case 15 the two would become to all intents and purposes a single sheet, and such a construction would be embraced in the term a "one-piece back plate" or "one-piece letter-shell."

Another important feature of this invention 20 is concerned with the formation of the box-like rim formed integral with the back plate. Said rim, comprising the riser *b*, facing *c*, and outer walls *d*, constitutes a girder or framework which accomplishes three purposes, to 25 wit: First, it strengthens and stiffens the entire back plate without adding much weight or any joints through which water may attack the interior wiring; second, it protects the sockets, inasmuch as it projects beyond the same, and, 30 third, it adds to the appearance by giving an impression of great weight and solidity and in addition furnishes a border to further set off the sign. By painting the riser *b* white or a light color it will act as a reflector to collect and direct the rays of light.

Having thus described my invention, what I claim as new, and desire to secure by Letters Patent, is—

1. In an electric sign, the combination with 40 a back plate; lamp-sockets secured thereto in letter outline; suitable feed-conductors for said sockets; and an open-bottom letter-out-
line shell housing said sockets and secured to 45 said back plate, the front of said shell being provided with apertures in alinement with the several housed sockets to receive the lamps, substantially as shown and described.

2. In an electric-light sign, the combination of a metal back plate; lamp-sockets secured 50 thereto in letter outline; an open-bottom let-
ter-outline shell, housing said sockets and secured to said back plate, the front of said shell being provided with apertures in alinement with the several housed sockets to re-

ceive the lamps and a rim upon said back plate; 55 said rim constituting a box-like border to strengthen and stiffen said back plate substantially as described.

3. In an electric sign, the combination of a metal back plate having a rim; lamp-sockets 60 secured thereto in letter outline, an open-bot-
tom letter-outline shell, housing said sockets and secured to said back plate, the front of said shell being provided with apertures in alinement with the several housed sockets to 65 receive the lamps, and the central letter-bearing portion of said back plate being depressed below the top of the rim sufficiently to bring the top of the sockets and housing below the top of said rim.

4. In an electric sign, the combination of a metal back plate; lamp-sockets secured thereto in letter outline, suitable feed-conductors for said sockets; an open-bottom letter-out-
line shell housing said sockets and secured to 75 said back plate, the front of said shell being provided with apertures in alinement with the several housed sockets to receive the lamp; and a raised rim formed integral with said back plate, the outer peripheral walls of said 80 rim being of greater height than the height of said rim above the center letter-bearing portion of the back plate whereby space is afford-
ed behind said center letter-bearing portion of 85 said back plate for the feed-conductors.

5. In an electric-light sign; the combination of a metal back plate; lamp-sockets secured thereto in letter outline; suitable feed-con-
ductors for said sockets; an open-bottom let-
ter-outline shell housing said sockets and se- 90 cured to said back plate, the front of said shell being provided with apertures in alinement with the several housed sockets to receive the lamp; a raised rim formed integral with said back plate, the outer peripheral wall of said 95 rim being of greater height than the height of said rim above the center letter-bearing portion of the back plate, and the rear edge of said outer wall having a flange, as *e*, whereby said back plate may be secured to an exterior 100 object, a space being thereby afforded between the plane of said flange and the center letter-bearing portion of said back plate for the purpose described.

CARL HALLER.
